(57) **CLAIM**

The ornamental design for an accessible bathtub, as shown and described.

DESCRIPTION

This application is related to U.S. patent application Ser. No. 12/432,543 titled “Accessible Bathtub” and filed on Apr. 29, 2009; and to U.S. Design patent application Ser. No. 29/336,219 titled “Accessible Bathtub” and filed on Apr. 29, 2009; and to U.S. Design patent application Ser. No. 29/336,221 titled “Door Bolster and Handles for Accessible Bathtub” and filed on Apr. 29, 2009; and to U.S. Design patent application Ser. No. 29/336,223 titled “Accessible Bathtub” and filed on Apr. 29, 2009.

FIG. 1 is a front perspective view of the claimed bathtub.

FIG. 2 is a rear perspective view.

FIG. 3 is a top plan view.

FIG. 4 is a front elevation view.

FIG. 5 is a side cross-sectional elevation at line 5—5 in FIG. 3; and,

FIG. 6 is a rear cross-sectional elevation at line 6—6 in FIG. 3.

The side cross-sectional view at line 5—5 in FIG. 3 to the right would be the mirror image of FIG. 5. The two handles are mirror images of each other. A bottom plan view would be devoid of surface ornamentation.

1 Claim, 3 Drawing Sheets

FIG. 1

FIG. 2

FIG. 6
